UNITED STATES PATENT OFFICE.

ADOLPHUS S. DENNIS, OF LAKEWOOD, OHIO.

COMBINED TYPE-WRITING AND COMPUTING MACHINE.

1,271,677.

Specification of Letters Patent.

Patented July 9, 1918.

Application filed July 22, 1912, Serial No. 710,853. Renewed November 8, 1916. Serial No. 130,276.

To all whom it may concern:

Be it known that I, ADOLPHUS S. DENNIS, a citizen of the United States, residing at Lakewood, in the county of Cuyahoga and State of Ohio, have invented a certain new and useful Improvement in Combined Type-Writing and Computing Machines, of which the following is a full, clear, and exact description, reference being had to the accompanying drawings.

This invention relates to combined type-writing and computing machines, wherein computing mechanism is set or operated for each actuation of a numeral key of the typewriter. One of the objects of the invention is to provide connecting mechanism between the numeral keys of the typewriter and the computer in such form that it shall not interfere with the numeral keys being operated by a touch of the same force as used to operate the letter keys. A disadvantage of combined typewriting and computing machines, as heretofore constructed, is that considerable extra force is required to depress the numeral keys over that required to depress the letter keys due to the necessity for operating the mechanism of the computer by numeral keys. This results, either in the numeral character being stuck too lightly on the paper, or the letter characters too heavily, or it requires a slow operation and constant attention by the operator to avoid this result. Sometimes, in the old mechanism, the effect was that the numeral keys, while actuating the computer, would not be depressed far enough to properly typewrite, thus giving a wrong computation for the matter typewritten. My invention does away with these defects.

To the above end, I provide in the connection between the typewriter and computer a series of clutches, one for each numeral key, and I mount these clutches between a series of continuously rotating shafts and a corresponding series of normally idle shafts adapted to operate the computer mechanism, and I arrange each clutch so that it is thrown into action by the depression of the corresponding numeral key of the typewriter. Accordingly, the numeral key lever is relieved of all extra work except that necessary to throw the clutch into action. In the mechanism devised by me, this work is very slight indeed, and is negligible in practical operation.

Other features of my invention contribute to the efficiency and simplicity of the device. A preferred form of the mechanism is shown in the drawings hereof and is hereinafter more fully described and such preferred form, as well as the invention in its broader aspect, is comprised within my invention and designed to be covered in the claims appended hereto.

In the drawings, Figure 1 is a plan of a combined typewriting and computing machine embodying my invention; Fig. 2 is a sectional end view thereof; Fig. 3 is a detail illustrating an end view of one of the operation clutches and the cams which operate the escapement for the computer carriage; Fig. 4 is a front view, partly sectional, of one of the clutches and mechanism operated by it; Fig. 5 is a plan of that portion of the connecting mechanism which stands beneath the typewriter; Fig. 6 is a rear elevation of a portion of the mechanism showing the escapement for the computing machine carriage; Fig. 7 is a detail of a safety device which may be used with each numeral key to insure a complete depression thereof in case the key has been depressed only partially but enough to start the actuation of the computing mechanism.

Figs. 1 and 2 illustrate, at 10, the frame of the typewriting machine. This machine may be of any ordinary type having keys with key levers 11 which operate type bars 12, or other printing device; 13 indicates the platen, which is shown as carried by the traveling paper carriage 14; 15 indicates the feet of the typewriter which are adapted to rest in suitable sockets 20 carried on the frame of the connecting mechanism. This enables the typewriter to be moved when desired and to be properly positioned when returned.

21 indicates the frame of the computing machine, and 22 the key board thereof. This key board is designed to be connected with suitable computing mechanism (not shown) within the frame, the keys being depressed to set the mechanism, and thereafter a suitable lever, indicated at 23, being operated to effect the computation, according to the keys set. Any of the well known type of computing mechanism may be used within the computer frame for effecting the result, as, for example, that

shown in my prior Patent No. 949,979, granted Feb. 22, 1910.

25 indicates a suitable traveling carriage for the computing machine. This carriage is connected with an escapement (hereinafter described) so that it moves from left to right a corresponding movement of the typewriting machine. Connected with the carriage are a series of rock shafts 30, on 10 each of which is a rock arm 31 designed to act downwardly on the key which stands beneath it and thereby depress and set the same. The rock shafts 30 telescope within and are splined to a series of rock shafts 33 15 which do not travel, but are mounted above the mechanism and designed to rock. It will be seen that by this mechanism the computer carriage, escaping within the typewriter carriage, will set the various 20 rock arms 31 successively over the different rows of keys 22, and that whatever the position of these rock arms, they may be operated to depress the computer bars by rocking the tubular rock shafts 33. The mechanism for rocking the rock shafts will now 25 be described.

The rock shafts 33 are rotatably mounted near one end in the frame bar 34 and near the other in the frame bar 35. On these 30 shafts are rock arms 36 (Figs. 3 and 4). These arms are connected by links 37 with cranks 38 on the series of shafts 39. The shafts 39 aline with a series of shafts 40 which are under constant rotation, and at 35 the junction of such shafts are suitable clutches controlled by the lever of the numeral keys of the typewriter, which, when thrown, connect the constantly rotating shafts with the shafts 39. When any clutch 40 is so thrown, the rotation of the shaft 39 rocks the shaft 33, and depresses the arm 31, depressing the corresponding key in the computing machine. At the end of the rotation, the clutch automatically withdraws 45 itself from action and the rotation of the shaft 39 stops. A suitable turn buckle 42 in the link 37 enables adjustment so that the proper actuation will be given to the key of the computing machine.

50 The constant rotation of the shaft 40 is provided by any suitable mechanism. For example, each shaft may have a gear 43, the various gears meshing with each other and the final shaft being geared, as shown in 55 Fig. 5, by the gears 46 and 47 with the shaft 48, which is shown as having a gear 49 meshing with a driving gear 50. This driving gear is shown as on a suitable hub 51 which receives a sprocket chain 52, which may lead 60 from a suitable motor, not shown. It is to be understood that for each alined pair of shafts 40, 39 there is a clutch adapted to connect the two shafts. I will now describe such clutch.

65 The clutches are illustrated in Figs. 2 to

5. As shown particularly in Figs. 3 and 4, on the end of the shaft 40 is a ratchet wheel 55. The hub of this ratchet wheel is extended so that there is a cylindrical recess beyond the end of the shaft providing a 70 bearing for the shaft 39. On the shaft 39 is a disk 56 having a hub 57 pinned to the shaft 39. On the face of the disk 56 is pivoted a pawl 58 which is adapted to engage with the teeth of the ratchet 55. A spring 75 59, secured to the disk, tends to force the pawl into engaging position. A flange 60 on the disk, preferably extends over the pawl and spring, and with the disk 61 incloses them. The pawl has a tail which 80 stands opposite an opening 65 in the flange 60. 62 indicates a lever having a downwardly extending nose adapted to enter such opening and thereby press the tail of the pawl downwardly and withdraw the 85 nose of the pawl from the ratchet wheel.

The lever 62 is shown in Fig. 3 as pivoted on a hinged bracket 64 and extending to the rear thereof and there provided with spring means tending to raise the rear arm of the 90 lever and thus depress the nose 63. In normal position the nose stands in the opening 65 against the pawl. This spring means referred to, as shown, consists of a link 66 connected with the lever 62 and surrounded 95 by a compression spring 67 compressed between a shoulder on the link and the base plate 68 of the frame for this mechanism.

The lever 62 is provided at its rear end with a laterally extending lip 69, furnishing 100 a shelf on which mechanism may thrust down to elevate the other end of the lever to release the clutch. Whenever the lip 69 is thrust downwardly, the rising of the nose 63 releases the pawl 58, which, under 105 the action of the spring 59 engages the ratchet wheel. This causes the members of the clutch to rotate together and thus gives a rotation to the shaft 39, rocking the shaft 33 and depressing the computer keys, as 110 heretofore explained. After the rotation has started, when the depressing force is removed from the lip 69, the spring 67 tends to return the lever 62 to normal position, and the nose 63 thereupon bears against the 115 flange 60 of the clutch and that flange rides beneath the nose until the rotation is almost completed. Then the nose springs into the opening in the flange and engages the tail of the pawl and forces the pawl out of engagement with the ratchet and the drive member of the clutch comes to rest. The nose 63 standing in the clutch 65 of the sleeve 60 acts as a stop to accurately position the driven member when at rest. The 120 lips 69 are depressed by the numeral keys of the typewriter by suitable mechanism, as will now be described.

It will be understood that one of the clutches described is provided for each shaft 130

39 and is adapted to connect it with the corresponding constantly rotating shaft 40. Accordingly, there is one clutch-operating lever for each key lever. As shown in Fig. 5, some of these levers 62 extend to the rear and others to the front. They may extend in either direction, as most suitable to enable them to be operated by the respective numeral keys of the typewriter.

10 Extending from front to back of the machine, above the shafts 40 and 39 and the interposed clutches, are a pair of supporting bars 70. On these supporting bars is mounted a suitable frame, consisting of a 15 bottom plate 71, a top plate 72, and corner members 73. This frame carries a series of plungers 75 (one for each digit) which are positioned to stand beneath the respective numeral key levers and above the 20 respective lips 69. Each plunger is given a pressure upward by a compression spring 76 between the spring members 71 and 72.

From the construction described it will be seen that, whenever a numeral key is 25 depressed, the lever 11 thereof, pressing downward on the plunger 75 beneath it, presses downward on the corresponding lip 69 of the lever 62 and releases the corresponding clutch connecting the corresponding shaft 30 39 with its alined, constantly driven shaft. This results in operating the corresponding numeral key of the computing machine.

As soon as the finger pressure is removed 35 from the typewriter key, the key lever returns to normal position, while the clutch goes on and completes its rotation and comes to rest at the end of such rotation, as will be apparent from the previous description. On the completion of the rotation of the 40 shaft 39, the rock arm 31 is raised by the link 37 from the numeral keys of the computer ready for the next action, the spring 32, acting on the rock arm 33, assisting in this operation.

45 To throw out the connection between the typewriter and computer whenever desired, I simply make the supporting bars 70 which carry the plunger frame movable. As shown, these bars are mounted on rock arms 50 80 and 81. This enables the bars to be shoved rearwardly, whenever desired, to carry the various plungers out of alinement with the various lips 69. Any suitable means may be provided to shift the device. 55 I have illustrated shifting means by a stem 82 connected with the bars and projecting through the frame of the mechanism and provided with a push button 84. Frictional, or other means, may hold these bars in the 60 position in which they are set. As shown in Fig. 2, the mechanism is active in the position shown, but idle when the push button 82 is pushed in and the bars 70 thereby moved rearwardly until they abut the rear plate 86 of the computer frame.

It is necessary that the computer carriage escape to the right, following each depression of one of the keys 22. This may be accomplished by any suitable escapement connecting with the various shafts 39. The 70 mechanism I have shown is simple and efficient and will now be described.

Referring to Fig. 6, 90 indicates a suitable escapement bar, connected with the computer carriage. 91 is a rock shaft on which 75 is a block or rock arm 92 carrying a stationary, rigid nose 93, and, alongside of it, a movable bar toward the right (Fig. 6) and a spring 96 tends to press it upwardly. At rest, a tooth of the escapement bar 90 rests 80 against the movable member 94, and by reason of the superior tension of the feeding spring (not shown) on the computer carriage, holds that bar at the limit of its movement, deflecting the spring 95, as shown in 85 Fig. 6. Such a feeding spring as above mentioned, is shown in my prior Patent No. 949,979; it is indicated at 213, Fig. 12 of that patent. Now, when the rock shaft 91 is rocked to bring the rigid projection 93 in 90 front of the tooth of the escapement bar, the spring 95 moves the movable projection toward the right (Fig. 6) and then, when the rock shaft 91 rocks backwardly, so that the stationary projection clears the tooth, the 95 movable projection swings onto the rear of that tooth. This frees the escapement bar and the same moves toward the left (Fig. 6) until the next tooth engages the movable spring 96.

Accordingly, the rocking of the rock shaft 91 first in one direction and then the other, actuates the escapement for the computer carriage and allows it to move from one line of numeral keys to the next. To rock 105 the rock shaft 91, I provide it with a rock arm 97, which carries a pin 98 engaging a lever 100. This lever is pivoted intermediate and at its lower end is connected with a sliding link 101, Figs. 2 and 5. On the 110 sides of this link are pins 102 projecting into the paths of cams 103 on the various shafts 39, the shafts passing through slots in the link. When any shaft 39 makes a rotation, the link 101 is thereby forced to the rear and 115 then returns to position (by reason of a tension spring 105 connected to the arm 106 in the rock shaft 91) and this rocks the lever 100 to rock the shaft 91 to actuate the escapement.

Accordingly, the depression of each numeral key not only releases the corresponding clutch, giving a single rotation to the corresponding shaft 39 to rock the shaft 33 to depress the key of the computer, but such 125 action is followed by an escapement of the computer carriage to bring the various arms 31 over the next row of keys thereon.

It may be desirable to provide means to insure the complete depression of any nu- 130

meral key when it has been depressed enough to release the clutch, even though such depression might not be enough to properly impress the corresponding character on the typewriter. To effect this I may provide the mechanism illustrated in Fig. 7. This illustration shows the plunger carriage 71, 72 provided with a set of depressible plungers 75, one for each key lever. Each of these plungers is adapted to rest on a lip of a lever 111, which carries an arm having a projection or pin 112 standing against a cam 113 on the corresponding shaft 39.

Now if the lever 11 be depressed sufficiently to release the clutch to rotate the corresponding shaft 39, the cam 113 thereon engaging the pin 112, swings the lever 111 and this, through the connecting link 114, draws down the key lever 11 to the end of its movement, resulting in properly printing the type character thereof. The cam 113 releases the lever 111 at the end of about a half-rotation so that the key lever has ample time to return to normal position. A slot 115 in this link enables the first portion of the depression of the lever 11 to be independent of the safety mechanism.

The device just described may be independent of the clutch lever 62 or consolidated with it, the horizontal arm of the clutch lever being in that case the arm 111 in Fig. 7, and the cam 113 in that case being on the side of the clutch 56.

Having thus described my invention, what I claim is:

1. The combination of a computing machine, a series of shafts corresponding to the different digits for actuating the computing machine, a typewriting machine, and a series of clutches adapted to connect said shafts with the numeral keys of the typewriting machine.

2. The combination of a computing machine, a typewriting machine, a connection between the numeral keys of the typewriting machine and the computing machine, including a series of clutches each adapted to impart a single complete rotation, mechanism for throwing them, and a series of shafts connected with said clutches.

3. The combination of computing mechanism, a typewriter, a series of shafts, one for each digit connected with the computing mechanism, a series of single rotation clutches, one for each shaft, and mechanism connected with the numeral keys of the typewriter for throwing said clutches.

4. The combination of computing mechanism having a series of operating members corresponding to the different digits, and a series of shafts, mechanism connecting the same with said operating members, whereby a rotation of the shaft operates the operating member, a series of clutches, one for

each shaft, a driving mechanism, a typewriter, and means under the control of the numeral keys thereof for connecting said driving mechanism with said shafts.

5. The combination, with a typewriter, of a computing machine having a series of depressible keys, mechanism including a series of rotatable shafts for depressing said keys individually, a series of constantly driven shafts alined with said rotatable shafts, normally idle clutches between them, and a connection between said clutches and the corresponding numeral keys of the typewriter.

6. The combination of a typewriter, computing mechanism, connecting mechanism between the two adapted to stand beneath the typewriter, said connecting mechanism including a series of operating shafts for the computing mechanism, a series of alined driving shafts, and a series of interposed clutches between the ends of alined shafts, a series of levers for throwing said clutches, and connections between said levers and key levers of the numeral keys of the typewriter.

7. The combination, with a typewriter having a series of operating members, means for actuating them, a carriage for moving said means from one series to another, a series of operating shafts for said means respectively, an escapement for the computor carriage connected with each operating shaft, and means actuated by the numeral keys of the typewriter for connecting the corresponding shafts with a driving device.

8. The combination, with a typewriter, of a computor having a plurality of series of operating members, means for actuating them, a carriage for moving said means from one series to another, a series of operating shafts for said means respectively, an escapement for the computor carriage connected with each operating shaft, a series of driving shafts alined with the shafts mentioned, a series of clutches between such alined shafts, and mechanism actuated by the numeral keys of the typewriter for throwing said clutches.

9. The combination of a computing machine, a typewriting machine, connecting mechanism between the two including a series of operating shafts and a series of clutches therefor controlled by the numeral keys of the typewriting machine, and mechanism operated by the rotation of one of said shafts for insuring the completion of the depression of a partially depressed numeral key.

10. The combination, with computing mechanism, of a typewriting machine, connecting mechanism between the two including rotatable shafts and clutches for operating them, of cams on said shafts, and connections between the same and the numeral

keys, whereby when the shaft is thrown into rotation the depression of the numeral key is insured.

11. The combination of a typewriting machine, a computing machine, connecting mechanism for actuating the computing machine and extending beneath the typewriting machine, power mechanism, a series of clutches for connecting the power mechanism with the connecting mechanism, a carriage having a series of plungers adapted to throw the respective clutches, said plungers being adapted to be actuated by the depression of the numeral keys of the typewriting machine, and means for moving said plunger carriage to idle position.

12. The combination in a computing machine, of a series of actuators, mechanism including a series of rotatable shafts for operating said actuators, a series of constantly driven shafts, a series of clutches between the corresponding shafts of the two series, and means for throwing said clutches.

13. The combination in a computing machine, of a series of actuators, mechanism including a series of rotatable shafts for operating said actuators individually, a series of constantly driven shafts alined with said rotatable shafts, clutches between said shafts, keys, and a connection between said clutches and said keys.

14. In a computing machine, the combination of a series of depressible keys, mechanism including a series of rotatable shafts for depressing said keys individually, a series of constantly driven shafts, normally idle clutches between each of the first mentioned shafts and the second named shafts,

a series of actuating keys, and a connection between said clutches and the corresponding actuating keys.

15. In a computing machine, the combination of a series of depressible keys, mechanism including a series of rotatable shafts for depressing said keys individually, a series of constantly driven shafts alined with said rotatable shafts, normally idle clutches between each of the first mentioned shafts and the second named shafts, and means for operating said clutches.

16. The combination of a computing mechanism, a series of shafts for operating the computing mechanism, a series of driving shafts, a series of interposed clutches between the driving shafts and the operating shafts mentioned, a set of numeral keys, and means operated by said numeral keys for throwing said clutches.

17. The combination of a typewriter, computing mechanism, connecting mechanism between the typewriter and computing mechanism, including a series of shafts for operating the computing mechanism, a series of driving shafts, a series of interposed clutches between the driving shafts and the operating shafts mentioned, and individual means operated by the key levers of the numeral keys of the typewriter for throwing said clutches.

In testimony whereof, I hereunto affix my signature in the presence of two witnesses.

ADOLPHUS S. DENNIS.
